CLAIM

I claim the ornamental design for a tray for a clipper case, as shown and described.

DESCRIPTION

FIG. 1 is a top perspective view showing my new design;
 FIG. 2 is a front view thereof;
 FIG. 3 is a left side view thereof;
 FIG. 4 is a right side perspective view thereof;
 FIG. 5 is a top view thereof; and,
 FIG. 6 is another perspective view thereof.
 The broken lines represent environment that forms no part of
 the claim.
